UNITED STATES PATENT OFFICE.

LOWELL H. RICE, OF CHICAGO, ILLINOIS.

MACHINE FOR SLITTING SHEETS OF PAPER OR THE LIKE.

SPECIFICATION forming part of Letters Patent No. 774,454, dated November 8, 1904.

Application filed July 24, 1903. Serial No. 166,814. (No model.)

To all whom it may concern:

Be it known that I, LOWELL H. RICE, of Chicago, in the county of Cook and State of Illinois, have invented certain new and useful Improvements in Machines for Slitting Sheets of Paper or the Like; and I do hereby declare the following to be a full and exact description thereof, reference being had to the accompanying drawings.

10 This invention relates to machines for slitting or cutting paper, bristols, or cardboards or the like.

Paper slitters or cutters of present usage operated by a lever cannot effect the clean accurate cut desired in cutting paper into equal-sized sheets. This lack of accuracy is due largely to the density of the paper forcing the cutting-knife out of its intended cutting-plane.

15 My invention consists, first, in the mechanism for cutting or slitting sheets of paper with accuracy.

It consists, second, in the mechanism for effecting a number of slits in one operation.

20 It consists, third, in the mechanism for regulating the number of slits to be made in one operation.

It consists, fourth, in the mechanism for regulating the distances between the slits when more than one is made in one operation.

25 It consists, fifth, in the mechanism for feeding the paper into the machine.

It consists, sixth, in the mechanism for smoothing the paper for presentation to the cutting edge with accuracy.

30 It consists, seventh, in the mechanism for forwarding and delivering the sheet after the operation of slitting has been performed.

It consists, eighth, in the various novel devices and combinations of the same herein illustrated and described, together with their mechanical equivalents, and pointed out with more particularity in the claims appended hereto.

35 In the drawings, Figure 1 is a perspective view of my machine. Fig. 2 is a plan view of one form of my invention with a portion of the feed-table broken away to show the working parts. Fig. 3 is a sectional view of my machine, taken through the line 3 3 of

Fig. 2 and looking toward the right. Fig. 4 50 is a view of the left side elevation of my machine as shown in Fig. 1 with the hand-wheel and belt-pulleys removed, showing the gears. Figs. 5, 6, and 7 are details showing the gripping mechanism of the front or cutting cylinder. Figs. 8, 9, and 10 are details showing the front guide and smoothing-brush. Fig. 11 is a cross-sectional detail of the rear or delivery cylinder, showing the clutching mechanism used for delivering the sheet after being cut. Figs. 12, 13, and 14 are details showing the particular construction of the upper or adjustable cutters, Fig. 12 being a front end view of one of the cutters, Fig. 13 being a sectional view of a cutter, taken 65 through the line 13 13 of Fig. 12, and Fig. 14 being a cross-sectional view of the cutter, taken across one of the cutters at a point shown at line 14 14 of Fig. 13.

More particularly described, A designates 70 the frame of the machine. It comprises side members each of which consists of two legs or standards A' and A'', the leg A' being somewhat longer than the leg A'', a connecting top member A³, a lower member A⁴, and intermediate cross members A⁵ and A⁶; said side members being joined together by upper and lower cross members A⁷ and A⁸.

The slitting or cutting mechanism of my invention is described as follows: It consists 80 of a series of upper cylindrical cutters B B B and a lower and coating cutting-cylinder C. The upper cutters B B are secured to the shaft B', which extends across the machine from side to side near the front and is secured 85 above the top members A³ A³ of the frame. The ends of the shaft B' are journaled onto the arms B² B², which rest upon the top members A³ A³ of the frame. These arms B² B² are pivoted at one end B³ B³ to the top of the 90 standards A² A² and extend backward upon the top members A³ A³. The free ends of the arms B² B² are fitted with adjusting-screws B⁴ B⁴, by the operation of which the arms B² B² can be turned upon the pivots B³ B³ and 95 the cutter-shaft B' be raised or lowered in its relation to the frame of the machine, thereby regulating the position of the cutters B B.

When the shaft is properly adjusted to the machine by the operation of the adjusting-screws B³ B⁴, it is held firmly in place by the clamps B⁶ B⁶, which are bolted to the top faces 5 of the top members A³ A³. One end of the shaft B' projects beyond the frame of the machine and is fitted with a gear B⁵.

The details of the upper cutters B B are illustrated in Figs. 12, 13, and 14 of the drawings and may be described as follows: Each cutter is cylindrical in form and is feathered onto the shaft B', as shown, b³, and may be firmly secured to said shaft B' by the action of the set-screws b⁴. The cutter B consists of 15 two parts b and b', made, preferably, of cast metal. The part b contains the set-screw b⁴ and may thereby be firmly secured to the shaft B'. The part b' bears the cutter-knife b² and is movably secured to the part b and is movable 20 upon the shaft B' within the limitations allowed by its connection with the part b, to be described. Both parts b and b' are bored and fitted to be feathered upon the shaft B'. The part b is fitted at one side with a deep recess, designed to receive a corresponding shank of the part b'. The part b' is fitted with a number of spring-seated posts b⁵ b⁵, which project beyond the surface of the shank of said part b' and toward the part b. The purpose 25 of the said posts b⁵ b⁵ is to hold the parts b and b' normally away from the point of their closest contact. The surface of the part b' and parallel with the spring-posts b⁵ b⁵ is fitted with an elongated slot b⁶. Through the 30 shell of the recessed portion of the part b and in relation to the slot b⁶ of the part b' is passed a screw b⁷, the lower end of which engages with the slot b⁶ and resting against the end of said slot holds the parts b and b' 35 in engagement one with the other. With the parts b and b' joined as just described the shank of b' lies within the recessed portion of the part b, but is held out of closest contact with the part b by the spring-posts b⁵ b⁵. If, however, power is applied to force the 40 parts into closest contact, the springs of the posts b⁵ b⁵ will yield to the pressure and the parts move into closer contact, the screw b⁷ sliding along the slot b⁶. With the pressure 45 removed, however, the parts will spring back to their normal position. This construction gives to the outward face of the part b' the property of resiliency. The cutter-knife b² is a circular band of hardened steel, the circumference 50 of which is ground to a slightly-bevelled edge. This knife is secured to the outward face of the part b' by means of the screws b⁸ b⁸, the portion of the knife through which the said screws b⁸ b⁸ pass being retired 55 from the plane of the cutting edge to prevent interference by the screws with the cutting edge of the lower cutting-knives to be described. The cutters B B may be removed 60 from the shaft B' by freeing the end of the shaft opposite the gear end from the clamp

B⁶ and the arm B². Then release the set-screw b⁴ and slide the cutter off the freed end of the shaft B'. The second or lower cutting edge consists of a cylinder C², lying below and parallel to said cutter-shaft B' and firmly secured to the shaft C', which passes from side to side of said machine and is journaled upon the intermediate cross members A⁵ A⁵. One end of the shaft C' extends beyond the surface of the frame A and bears the gear C⁵, 75 which coacts with the gear B⁵ of the cutter-shaft B'. The cylinder C² consists of two heads C³ C³, one of which is rigidly secured to the shaft C' and the other feathered upon said shaft, and a series of cylindrical cutters 80 CCC, feathered upon said shaft C' intermediate the heads C³ C³ and separated from the heads C³ C³ and from each other by the washers C⁴ C⁴. The cutters are held tightly in position between the heads C³ C³ upon the shaft 85 C' by means of a series of tie-bolts C⁷ C⁷, which pass through the cutters CCC and secure them to the heads C³ C³. The cutters CCC may be adjusted in position upon the shaft C' by releasing the tie-bolts and then inserting 90 and removing the washers C⁴, which are slotted to pass around the shaft C' and the tie-bolts C⁷ C⁷. Then the whole may be again locked and when so locked presents a solid cylindrical surface, the cutters CCC protruding beyond the washers C⁴, the latter being the smaller in diameter. The cutters CCC consist of disks c c, bored to accommodate the shaft C' and the bolts C⁷ C⁷, and knives c' c', 95 consisting of circular bands of approximately 100 the same diameter as the disks c c and secured one upon the same face of each of the disks c c by screws c² c². The circumference of the disks c c presents a smooth surface intended to bear the sheet of paper during slitting, and the circumference of the knives c' c' presents a beveled edge which coacts with the edge of the cutters B B. The disks c c are recessed, C⁶, to accommodate the gripping device to be hereinafter described. 110

The delivery-cylinder D² is intended to carry away the sheets of paper after the slitting operation and is described as follows: The delivery-cylinder D² lies immediately back of and parallel with the cutting-cylinder C², is of equal diameter therewith, and is supported by the shaft D', which is journaled to the intermediate cross members A⁵ A⁵, and the shaft D' bears on one end the gear D⁵, coacting with the gear C⁵ of the cutting-cylinder 115 C². The delivery-cylinder consists of two heads D³ D³ and a series of wheels D, set at suitable distances apart and adjustably secured to the said shaft D' by means of set-screws. The circumferences of the wheels 120 D D present smooth surfaces. Each wheel D D is recessed, D⁶, to receive the delivery-grippers, as hereinafter described. The gear D⁵ is adjustably connected to the end of the shaft D', as is indicated at D⁴, which adjust- 125 130

ment has for its purpose the accurate regulation of the action of the cylinder D² in relation with the cutting-cylinder C².

Carrying paper into and through a machine 5 is a more difficult operation than that of carrying mill-boards or other stiff materials, which may be fed through by pushing. Paper, having little or no stiffness, should be pulled through the machine. I have therefore adapted for that purpose in my invention 10 two series of grippers E and F, the former being attached to the cutting-cylinder and the latter to the delivery-cylinder. The grippers E are intended to grasp the paper sheet by 15 its forward edge when it enters the machine and hold it until the sheet is slit and ready to be transferred to the delivery-cylinder D². The construction of the grippers E may be described as follows: A shaft e passes through 20 the recesses C⁶ of the disks c c of the cylinder C² and through suitable perforations in the other parts of the cylinder C² and is journaled in the cylinder-heads C³ C³. Fitted upon this shaft e and corresponding in position with the 25 recesses C⁶ C⁶ are a number of finger-shaped grippers e' e' e', each provided with a set-screw e². These grippers e' e' are designed to clamp upon the surface of the disks c c at intervals in the operation of the machine and 30 at other intervals to retire below the surface of said disks c c and into the recesses C⁶ C⁶. One end of the said shaft e protrudes from the outer face of said head C³, and attached thereto at its center is a slotted tumbler e³. 35 To one end e⁴ of the tumbler is pivoted the end of a spring-post e⁵, the other end of which post passes through an eyebolt e⁶, secured to the outer face of the cylinder-head C³. Said eyebolt e⁶ forms a shoulder against which 40 rests one end of the spring e⁷ of the post e⁵. Protruding from the frame of the machine and coacting with said tumbler e³ are two studs e⁸ and e⁹. In its relation to the shaft e the stud e⁸ stands outside the plane of the 45 circle described by said shaft e in the rotation of the cylinder C² and the stud e⁹ lies within such plane, as is shown in Fig. 5 of the drawings. In the rotation of the cylinder C² upon the approach to the position 50 of the stud e⁸ the grippers e' lie in a retarded position within the recess C⁶. The tumbler e³ lies in such a position that the end opposite to that to which the spring-post e⁵ is attached is extended upward and forward. When the 55 position of the stud e⁸ is reached, the upward projecting end of the tumbler e³ strikes the stud e⁸, which slides into the slot of said tumbler e³. The shaft e passing beneath the stud e⁸ forces the tumbler e³ to describe the arc of 60 a circle forward and under the stud e⁸, the spring-post e⁵ yielding to the pressure. With this arc described the stud passes out of the slotted tumbler e³. This action throws the grippers e' e' out of the recess C⁶ C⁶ and into 65 a clamping position upon the surface of the

disks c c of the cylinder C². They are held firmly in this position by the action of the spring-post e⁵, it having exerted its power after having passed the center formed by the eyebolt e⁶ and the shaft e in the above-described movement. The grippers e' e' are thrown out of the above-described engagement when in the further rotation of the cylinder C² the tumbler e³ strikes the stud e⁹. When the tumbler e³ approaches the stud e⁹, 70 the forward end e⁴ is projecting downward or inward toward the stud e⁹. When the position of the stud e⁹ is reached, the forward end of the tumbler strikes the stud e⁹, which passes into the said slot. The shaft e then passes 75 above the position of the stud e⁹ and is forced to describe a segment in a manner the reverse of the action caused by the stud e⁸, described hereinbefore. The stud e⁸ is so placed upon the frame of the machine as to throw the grippers e' e' into clamping position at the point where the paper sheet enters the machine. The stud e⁹ is so placed as to throw the grippers out of position and release the paper when 80 the operation of slitting shall have been completed and the paper is ready to be delivered to the cylinder D². The action of disengagement of the grippers e' e' must be in exact relation with the gripping device F of the delivery-cylinder D², which grips and takes up 85 the slit sheet upon its release by the gripping device E. 90

The gripping device F, as suggested, is intended to take up the slit sheet when released by the gripping device E and hold it in position on the delivery-cylinder D² while being passed out of the machine. It is described as follows: A shaft f passes through the recesses D⁶ in the wheels D and is journaled within the heads D³ D³. Upon this shaft f are fitted the 100 grippers f' f', one of which lies upon the shaft f in relation to each of the wheels D. The grippers f' are fitted with screws f², which permit adjustment of the grippers. One end of the shaft f protrudes beyond the 105 outer face of the head D³ and is fitted with a crank or lever arm f³, which has on its free end a small roller f⁴. This roller f⁴ lies in relation to and coacts with the cam f⁵, which is attached to the frame of the machine and adjacent to the head D³. This cam f⁵ is secured to the frame of the machine in some adjustable manner, as shown at f⁶ f⁶. This adjustment permits of the regulation of the time of action 110 of the gripping device F. Adjacent to the lever f³, but at an angle therewith, there is attached to the said shaft f another crank or lever arm f⁷. To the free end of the lever-arm f⁷ there is pivoted one end of a spring-seated post f⁸, the other end of which passes through an eyebolt f⁹, secured to the head D³. The said eyebolt f⁹ acts as a shoulder for one end of the 115 spring of said post f⁸. The levers f³ and f⁷ are arranged upon the shaft f at such an angle that when in the rotation of the cylinder 120 125 130

D² the roller f⁴ engages with the cam f⁵ the grippers f' f' are held upward and out of contact with the face of the wheels D D and the spring of the post f⁸ is compressed. When in the further rotation of the cylinder D² the roller f⁴ passes away from contact with the cam f⁵, the spring of the post f⁸ asserts itself and the grippers f' f' are thrown into clamping position upon the face of the wheels D D. The cam f⁵ is so arranged that in the rotation of the cylinder D² the roller f⁴ leaves the cam f⁵ at the time when the grippers f' f' come adjacent to the cylinder C², and the paper sheet is released from the grippers e' e' of the said cylinder C². The grippers f' f' then take up the paper sheet and carry it upon the delivery-cylinder D² to the point where it meets the receiving-table R, at which time the roller f⁴ again engages with the cam f⁵, and the grippers f' f' are thrown upward and out of engagement, and the paper sheet passes from the cylinder D² onto the table R with the operation completed.

I provide in my invention a feed-table T, which consists of a broad smooth sheet of wood or metal secured upon the top members A³ A³ of the frame and inclined toward the cutting mechanism, hereinbefore described. The forward edge of the table T projects over the cutting-cylinder C² and has affixed to its forward edge a thin sheet of metal t, which is slotted along its forward edge to allow the grippers e' e' e' to grip the paper sheet upon the cylinder C² before the front edge of such paper sheet passes from such slotted projection t. The paper sheet, which is illustrated as P in the drawings, is placed upon the inclined table T, and I must provide some means of regulating the position of the forward edge of such sheet P when it is gripped by the grippers e' e'. I therefore provide the guides G G, (shown in detail Figs. 9 and 10,) described as follows: The guides are several in number and each consists of two parts g and g', the former of which telescopes into the latter. The part g carries at one end a guide-plate g², against which the paper sheet is made to rest. The part g' is a tube into one end of which is telescoped the part g, and the other end is fitted with an adjusting-screw g³, which engages g and by means of which g is regulated. The clamp-screw g⁴ is intended to clamp the part g in adjusted position. The part g' is affixed to a shaft g⁵ and held in position thereon by a clamp-screw g⁶. The shaft g⁵ extends across the frame of the machine in front of the cutting mechanism and is journaled onto the top members A³ A³. One end of the shaft g⁵ projects beyond the outer face of the top member A³ at the side adjacent to the gears, hereinbefore described, and bears a lever-arm g⁷, fitted at its free end with a small roller g⁸. This roller g⁸ engages with a cam g⁹, which is secured to the inner face of the gear C³. The part g of the guide projects

from the shaft g⁵ toward the cutting mechanism and in normal position is designed to rest upon the slotted projection t of the table T, as shown in Fig. 9. When, however, in the rotation of the gear C³ the cam g⁹ comes into contact with the small roller g⁸, the shaft g⁵ is rotated backward from the cutting mechanism, thereby lifting the part g free from the projection t. This is shown in Fig. 10 of the drawings. The guides G G normally lie upon the slotted end of the table T, and against the guide-plate g² g² the sheet P is made to slide and straighten for its even entrance into the machine when caught by the grippers e' e'. The cam g⁹ is so placed upon the gear C³ that in operation it engages the small roller g⁸ and lifts the guides G G from the table at the moment the grippers e' e' engage the sheet P. When the sheet P shall have passed into the machine, the roller g⁸ is disengaged from the cam g⁹ and the guides of their own weight drop onto the table and catch and adjust the succeeding sheet P.

Paper having little rigidity and being highly flexible, it is found necessary to provide some means of flattening or smoothing the sheets P from any unevenness of surface accruing from careless handling. For this purpose I provide a brushing device H, which lies just behind the guides G and is designed to drop onto the paper sheet P just previous to its being taken up by the grippers e' e' and the guides G G raised from the table T. This brushing mechanism consists of a brush h, curved arms h', the shaft h², the lever-arms h³ h⁴ h⁵, and the cam h⁶. The brush h is a long narrow brush which lies parallel to the cutting-cylinder C² and extends the width of the machine. It is attached by knuckle-joints to two curved arms h' h', which are so curved that the brush h may rest upon the paper sheet P lying upon the table T and the arms h' h' may pass over the upper cutter B B and be attached to a shaft h², which is secured to the frame of the machine and in front of the said cutters B B. This shaft h² is journaled to the upper end of the standards A² A² or upwardly-extended projections therefrom. The arms h' h' are permanently attached hereto. The cam h⁶ is attached to the shaft C', and an engagement of the said cam h⁶ with the shaft h² is effected through the medium of the lever-arms h³, h⁴, and h⁵, forming a compound lever by means of which in operation the brush h is raised from the paper sheet P and again allowed to drop upon it. The cam h⁶ is so placed upon the shaft C' that in operation the lever-arm h⁵ engages said cam h⁶ and lifts the brush h from the table t after the paper has passed into the machine at the moment the guides G G drop onto the table T to receive the succeeding sheet P. The cam h⁶ passes out of engagement with the lever-arm h⁵ and permits the brush h to drop of its own weight onto the sheet P just previous to the time the grippers

e' e' take the sheet *P*. The knuckle-joints by which the brush *h* is joined to the arms *h' h'* prevent the weight of the arms *h' h'* adding to the pressure upon the sheet *P* in case of 5 faulty adjustment of the parts. This adjustment is secured in the lift-dog or lever-arm *h³*, which is adjustably secured to the shaft *h²*.

In order to hold the paper smooth upon the delivery-cylinder *D²* and prevent buckling or 10 misplacement while the sheet *P* is being carried upon said delivery-cylinder, I provide a roller *J*, which is secured in some desirable manner to the frame of the machine and lies in close proximity to the cylinder *D²*, as shown 15 in Fig. 3 of the drawings.

The driving mechanism *K* of my machine is fitted upon the outside of the frame of the machine and has operative connection with the gears *B⁵ C⁵ D⁵*, hereinbefore described. 20 The mechanism is described as follows: To the end of the frame of said machine adjacent to the gears, hereinbefore described, I affix a yoke *k*. Extending from the outer side of this yoke to the intermediate side member *A⁶* 25 and journaled to the said yoke *k* and member *A⁶*, respectively, is a shaft *k'*. The shaft carries a gear *k⁵*, which coacts with the gear *C⁵*, hereinbefore described. Upon this shaft *k'* and within the yoke *k* are fitted two belt-pulleys *k² k³*, the pulley *k²* revolving freely upon 30 said shaft *k'* and the pulley *k³* being firmly affixed to said shaft and carrying said shaft *k'* with it in its revolutions. These pulleys *k²* and *k³* lie in close relation with each other, 35 and it is designed that the power-belt may be shifted from one to the other with ease. This transfer of the power-belt is accomplished by a shifting device *k⁴*, consisting of a fork embracing said belt, operated by a handle and 40 lever attached to the frame of the machine. When the belt is in contact with the pulley *k²*, the machine is at rest and out of contact with the power, inasmuch as the pulley *k²* is arranged to revolve upon said shaft *k'* as an 45 axle. Upon the transfer of the belt to the pulley *k³*, which is firmly attached to the shaft *k'*, the power is applied to the machine, which is at once set into operation. Upon the shifting of the belt back to the pulley *k²* the machine 50 is released from the power and comes to rest. To the outer end of the shaft *k'* I affix a hand-wheel *k⁶*, by which the machine may be moved when released from the motive power.

55 My machine is designed to slit a sheet of paper into two or more smaller sheets and the regulation of the size and number of the product-sheets is effected by the adjustment of the cutters *B B* and *C C*. The upper cutters *B B* can be moved along the shaft *B'* or removed from the shaft, if desired, and after adjustment to the required position one with the other they may be adjusted nicely to the lower cutters *C C* by the removal or insertion 60 of the washers *C⁴*. The cutters *C* and *B*

should be adjusted to overlap each other a short distance, and this adjustment is effected by raising or lowering the shaft *B'* by the adjusting-screws *B⁴ B⁴*.

I claim as my invention—

1. In a paper-slitting machine, means for slitting paper and the like, consisting of a cylinder fitted with a series of cutting edges and coacting with said edges, rotary cutters seated upon a shaft and consisting each of two 75 parts, the one adjustably secured to said shaft and the other, bearing the knife or cutting edge and having resilient connection with said adjustable part, consisting of a shank passing into a suitable recess in said adjustable part, a screw fitted in said knife-bearing part, the head of which screw is slidably retained in an elongated slot in said adjustable part, and spring-seated posts holding said parts normally away from the point of closest contact, 80 and means for adjusting said cutters upon said shaft and means for actuating said shaft and said cutting-cylinder.

2. In a paper-slitting machine, means for slitting paper and the like, comprising a series 90 of rotary cutters and coacting therewith a cutting-cylinder, consisting of a shaft journaled as to its ends to the frame of the machine, two cylinder-heads, one permanently secured to the said shaft near its end, the other feathered 95 upon said shaft, intermediate the said heads a series of circular knife-frames feathered upon the said shaft and presenting at their peripheries smooth surfaces, circular knives attached to the said knife-frames, means for adjusting 100 the said knives upon the said shaft, consisting of washers of different thicknesses inserted between the said knife-frames, tie-bolts securing the parts of the said cutting-cylinder and means for actuating the said rotary cutters 105 and the said cutting-cylinder.

3. In a paper-slitting machine, the combination with cutting-cylinders and means for operating the same a feed-table and adjustable paper-guides *G, G*, and means for actuating the same consisting of a shaft bearing said guides and journaled to the frame of the machine parallel with and immediately in front of the said cutting-cylinders, a crank-arm fitted upon one end of the said guide-shaft, and having relation as to its free end with a cam attached to one of the gears of the said machine and means for actuating said guides and means for adjusting them upon the said guides. 110

4. In a paper-slitting machine the combination with cutting-cylinders and means for operating the same and a feed-table, of an automatic paper-smoothing device consisting of a brush supported by a number of arms fixed to a rotating shaft, and means for automatically rotating said shaft, whereby said brush is raised from and lowered onto the said feed-table. 115

5. In a paper-slitting machine, the combi- 120

nation with cutting-cylinders and means for operating the same, and a feed-table, of an automatic paper-smoothing brush, consisting of a long, narrow brush designed to rest upon the paper sheet upon the feed-table, which brush is attached at its ends by knuckle-joints to two curved arms, which extend over the cutting-cylinders and are attached to a shaft which lies in front of the cutting-cylinders and is journaled to the frame of the machine, and a compound lever attached to said shaft and giving it relation with a cam attached to one of the gears of the said machine, and means for operating the same.

15 6. A paper-slitting machine consisting of a cutting-cylinder and coacting therewith a series of rotary cutters, a feed-table, automatic paper-guides, an automatic sheet-smoothing brush, a delivery-cylinder, two series of paper-grippers fitted respectively to the cutting-cylinder and the delivery-cylinder and oper-

ating in relation with each other, a receiving-box, gears fitted to the said rotary cutters, the cutting-cylinder and the delivery-cylinder and operating in relation one with the other 25 and with a power-gear, and means for actuating the said gears.

7. A paper-slitting machine consisting of a cutting-cylinder and coacting therewith a series of rotary cutters, a delivery-cylinder, 30 a feed-table, automatic paper-guides, an automatic smoothing-brush, two sets of automatic grippers, a receiving-box and means for actuating said cylinders and series of rotary cutters consisting of interlocking gears to 35 which motive power is applied, substantially as described and for the purposes herein set forth.

LOWELL H. RICE.
